UNITED STATES PATENT OFFICE.

ELI B. BARTH, OF UPPER SANDUSKY, OHIO.

HOG-TROUGH.

1,182,239.

Specification of Letters Patent.

Patented May 9, 1916.

Application filed February 14, 1916. Serial No. 78,221.

To all whom it may concern:

Be it known that I, ELI B. BARTH, a citizen of the United States, residing at Upper Sandusky, in the county of Wyandot and State of Ohio, have invented certain new and useful Improvements in Hog-Troughs; and I do declare the following to be a full, clear, and exact description of the invention, such as will enable others skilled in the art to 10 which it appertains to make and use the same.

This invention relates to new and useful improvements in feed troughs for hogs.

One object of the invention is to provide 15 a feed trough which has its open top provided with a plurality of horizontally adjustable slats which are adapted to provide feed spaces of different widths according to the size of the pigs or hogs to be fed from 20 the trough.

Another object of the invention is to provide a trough of this character having an improved cover which is removable attached thereto, and said cover when removed from 25 over the feed spaces of the trough, is adapted to be vertically positioned above the same so that it may always be easily accessible when desired for use.

A further object of the invention is to 30 provide a device of this character which is simple and durable in construction, easy to manufacture, and one which will be very efficient in operation.

With these and numerous other objects in 35 view, my invention consists of the novel features of construction, combination and arrangement of parts which will be herein referred to and more particularly pointed out in the specification and claims.

40 In the accompanying drawings: Figure 1 is a front elevation of my invention; Fig. 2 is a top plan view of the same; Fig. 3 is an end view; Fig. 4 is a transverse section taken on the line 4—4, of Fig. 2 showing the 45 cover in position; Fig. 5 is a transverse section taken on the line 5—5 of Fig. 2 showing the cover removed and held vertically above the trough; Fig. 6 is a transverse section taken on the line 6—6 of Fig. 2 showing the 50 inlet in open position; Fig. 7 is a perspective view of one of the spacing members; and Fig. 8 is a detail perspective view of a portion of the upwardly projecting notched flange which is secured to the edge 55 of the front side of the trough.

In describing my invention, I shall refer to the drawings in which similar reference characters designate corresponding parts throughout the several views and in which the numeral 1 designates a substantially V-shaped feed trough, one of its sides 2 being substantially longer than its opposite side 3. The feed trough 1 is provided with ends 4 which project laterally from either side of said trough and are adapted to form a support therefor. Secured to the outer surfaces of the ends 4 at either end of the trough are standards 5 which rise therefrom a predetermined distance above the trough, and are connected at their upper ends by 70 means of a horizontally extending substantially inverted L-shaped ridge 6 which is centrally disposed above said trough. This ridge 6 is provided throughout its horizontal length with a plurality of spaced apertures 7 for a purpose to be hereinafter more fully described. This ridge 6 is slightly longer than the trough and standards, and projects at either end a short distance beyond the said standards. The projecting 80 ends of the horizontal portion of the ridge 6 are provided with notches 8 for a purpose to be hereinafter more fully described.

The standards 5 are provided with inclined faces 9 which extend from the upper 85 edge of the same downwardly to a point adjacent the edge of the side 3 of the trough 1. These inclined faces 9 terminate in laterally projecting shoulders 10, and positioned below the shoulders 10 and secured in 90 the outer surface of the standards are laterally projecting studs 11. The inclined faces 9 are adapted to receive a removable cover 12 which is adapted to be held over the trough 1 thereby, the lower edges of 95 said cover engaging the shoulders 10, while the upper edges of the same are adapted to lie flush with the top of the ridge 6 at the top of said standards. This cover 12 is substantially the same length as the ridge 6, 100 and the projecting portions of the same have secured to their under sides downwardly and laterally projecting extensions 13 which, when the cover is positioned against the inclined faces 9 of the standards, will project 105 past the same and will coact with the studs 11 to prevent the said cover from being lifted from over the trough. To remove the cover, it is necessary to swing the same forward, whereby the standards 13 will be 110

5 moved away from the studs 11, then the cover may be lifted from off the standards, and the extensions 13 are adapted to be received in the sockets 8 at the opposite ends of the ridge, so that the cover will be held vertically above the trough, and will always be easily accessible when it is desired to place the same in position again.

10 The outer edge of the side 3 of the trough 1 has secured thereto an upwardly projecting flange 14, which has in its outer edge a plurality of notches 15 which correspond with the apertures 7 in the ridge 6. This ridge 6 has its vertical downwardly extending portion 16 positioned on the upper edges 15 of the ends 4 of the trough.

15 This trough is adapted to be divided into a plurality of feed spaces by means of division slats 17, which are adapted to extend 20 from the flange 14 on the outer edge of the side 3 of the trough, to the lower surface of the ridge bar which is disposed above said trough. These slats 17 have their lower ends 18 provided with an extension 19 which 25 projects from the front portion of the same, and the said lower ends are also provided with transversely extending notches 20 which are crossed intermediate their ends by rods 21. Between the transversely extending notches 20 and the portion of the 30 lower ends adjacent the extension, are longitudinally extending slots 22 which are adapted to receive plates 23. These plates 23 project laterally from either side of the 35 slats at the lower ends of the same, and have their inner surfaces adapted to, when the slats are in position, lie flat against the upper surface of the flange 14, on the outer edge of the side 3 of the trough. The plates 40 23 are provided with downwardly projecting inclined shoulders 24 which extend from opposite sides of the slats 17 a predetermined distance for a purpose to be herein-after described. The rods 21 which are disposed in the transversely extending notches 45 20 in the lower ends of the slats are adapted to be positioned in the notches 15 in the flange 14, so that the lower ends of the slats will be securely held by the same.

50 The inner and outer sides of the slats 17 converge inwardly to a central point at their upper ends, and are formed at an angle which corresponds to the angle formed by the lower surface of the ridge 6. These 55 upper ends of the slats which are designated by the numeral 25 are positioned in said angle, and on account of the fact that the lower ends of the slats are positioned in one of the notches in the flange on the 60 trough, and owing to the fact that the said notches are in corresponding alinement with the apertures 7 in the ridge bar, the upper ends of said slats will be positioned directly beneath the apertures in said bar. These 65 upper ends 25 are provided with longitu-

dinally extending slots 26 which are in direct alinement with the said apertures, so that pins 27 are adapted to be positioned through said apertures and into the slots to hold the slats in position. These slats 17 are adapted 70 for various positions by the above described means along the trough, and they may be varied to increase or decrease the width of the feeding spaces, according to the size of the pigs or hogs which are desired to be fed. 75 The preferred manner of attaching these devices, is to secure three of these slats at equally spaced intervals along the trough, and to so dispose the notches between the same, that either one, two, or three slats are 80 equally spaced therebetween, according to the size of the animals which are desired to be fed. The fastening means above described afford a very simple and easily manipulated form of removable fastener, so 85 that the slats may be readily adjusted as desired. The sloping shoulders 24 at the upper ends of the plates 23 will prevent the pigs or hogs from stepping into the trough, owing to the fact that their feet will slide 90 toward each other and cross immediately upon coming in contact with said shoulders, so that the animal will hastily withdraw. This will prevent any possibility of the pigs or hogs entering the trough in any manner. 95

This trough is provided with a food inlet above the side 2 which is covered by a strip extending the entire length of the trough, which is adapted to swing back and forth over the inlet which is between the edge of the side 2 of the trough, and the lower end of the vertical portion 16 of the ridge 6. This strip 28 has sloping upper and lower edges 29 and 30, and is provided adjacent its ends with laterally extending bars 31. 100 The strip 28 when in closed position over the opening, as clearly shown in Figs. 2, 3 and 4 of the drawings, has its upper edge 30 disposed adjacent to and lying flush with the lower outer side of the vertical portion 110 16, and the lower end 29 of the same is positioned within notches 32 in the upper surface of the ends 4 of the trough. These notches 32 are substantially U-shaped, and are positioned at the opposite ends of the 115 upper edge of the side 2 of the trough. The notches have inclined front and rear side faces 40 and 41. The sides 40 of the notches 32 are substantially the same height as the strip or cover 28, so that when the same is in 120 open position the upper edge of said strip or cover will lie flush with the upper edge of the sides 40. Studs 33 project laterally from the inner sides of the projecting portions at the rear of the ends 4, and are adapted to coact with the projections or extensions 31 on the strip 28, which are positioned directly beneath the same when the said strip is in closed position, so that the strip 125 is not easily movable, and cannot be lifted 130

directly from over the opening. When it is desired to open the spaced cover thereby to pour food into the trough, it is only necessary to press down on the extensions 31, whereby the strip will pivot on its lower edge 29 and will swing back and away from the vertical portion 16 a certain distance, and the said lower edge of the strip will slide down and be positioned in the notches 32, which conform substantially to the shape of the same so as to securely hold the strip in position. The extensions 31 will then be disposed adjacent the outer side of the side 2 of the trough, while the upper edge of the strip 28 will lie flush with the extreme upper point of the extensions on the ends 4 of the trough. When in this position, it will be easy to pour food into the trough, as a continuous sloping surface will be presented to direct the same to the bottom of the feed holder. If desired, the strip 28 may be provided with a fastening means 35 intermediate its ends, which, when the strip is in closed position, is adapted to turn so as to engage an opening 36 in the outer wall of the vertical portion 16, so that the closure formed by this strip 28 will be securely held in locked position. The removable cover 12 which is disposed over the feed spaces of the trough may be, if desired, also held in position by means of a fastening member 37 which is secured to the top of the ridge 6, and is adapted to project over the upper edge of said cover when the same is in closed position.

By the above described means, it will be seen that I have provided a feed trough for hogs and pigs of various sizes, that embodies a novel arrangement of parts which are very easy and simple to construct, and the said device is provided with an extremely simple form of adjustment to vary the different widths of the feed spaces over the top of the trough. It will be noted that this type of trough does not involve the use of hinges which are liable to rust and break, and the structure employed in the same is reduced to a very simple form.

From the foregoing description of the construction of my improved device, the manner of applying the same to use and the operation thereof will be readily understood, and it will be seen that I have provided a simple, inexpensive and efficient means for carrying out the objects of this invention.

I claim as my invention:

1. A device of the class described comprising a trough, standards secured to the ends thereof, a ridge connecting the upper ends of said standards, an upwardly projecting flange having a spaced notched upper edge on the front edge of the trough, slats having transversely extending recesses in their lower ends adapted to engage the upper edge of said flange, rods extending

across said recesses and positioned in said notches in the flange, and the upper ends of said slats removably engaging the ridge.

2. A device of the class described comprising a trough, standards secured to the ends thereof, a ridge connecting the upper edge of said standards, an upwardly projecting flange having a spaced notched upper edge on the front edge of the trough, slats having extensions on the outer portions of their lower ends projecting below the same, the portions of said ends adjacent the extensions having longitudinally extending slots therein, plates positioned in said slots and extending to the lower edge of said extensions, inclined shoulders on said plates projecting laterally from either side of the slats, said lower ends of the slats having transversely extending recesses therein adjacent the slots, cross rods for said recesses adapted to be positioned in the notches in said flange, and the upper ends of said slats removably engaging the ridge.

3. A device of the class described comprising a trough, standards secured to the ends thereof, a ridge having a vertical portion and a horizontal portion connecting the upper ends of said standards, said horizontal portion of the ridge having spaced apertures therethrough, an upwardly projecting flange having a spaced notched upper edge on the front edge of said trough, slats having their front and rear sides converging inwardly at their upper ends to form an angle corresponding to the angle of the ridge and positioned therein, said angular upper ends having longitudinally extending slots disposed beneath the apertures in the horizontal portion of the ridge, pins positioned through said apertures and slots to hold the upper ends of the slats in position, and means to removably position the lower ends of said slats in the notches in the flange on the front edge of the trough.

4. A device of the class described comprising a trough, standards secured to the ends thereof having downwardly inclined front edges, laterally projecting shoulders at the lower ends of said inclined edges, studs on the outer surface of said standards below the shoulders, a ridge connecting said standards, a removable cover positioned on said inclined edges with its lower edge engaging said shoulders and its upper edge lying flush with the ridge, the ends of said cover projecting beyond the standards, downwardly projecting extensions on said ends normally positioned beneath said studs on the standards, and said ridge having notches in its ends to receive said extensions when the cover is removed from the trough so that the same may be positioned vertically with respect to the same.

5. A device of the class described comprising a trough, standards secured to the

ends thereof and connected by a ridge, said extensions having substantially U-shaped notches in their upper edges adjacent the ends of the edge of the rear side of said trough, the rear side wall of said notches being longer than the front side wall, studs projecting inwardly from said standards adjacent the rear wall of the notch, a cover for the opening between said edge of the trough and the ridge having inclined upper and lower edges with its lower edge positioned in said notches and adapted to swing

therein, and downwardly projecting bars adjacent the ends of said cover projecting therefrom and normally positioned beneath the studs on said standards.

In testimony whereof I have hereunto set my hand in presence of two subscribing witnesses.
